DOOR LATCH FOR MODULAR CABINET
Lawrence J. Fay, Elgin, Ill., assignor to Equipco Electronics Corporation, Naperville, Ill., a corporation of Illinois

Filed Oct. 30, 1961, Ser. No. 148,618
5 Claims. (Cl. 70—82)

The present invention relates generally to a locker cabinet and more particularly to a door handle and latching mechanism.

The present invention is concerned with a new and improved latching mechanism presently illustrated for use with a door which is adapted to lie flush with a forward wall of a locker cabinet.

An important object of this invention is to provide a new and improved latching mechanism which may be economically manufactured with a minimum of parts.

Still another object of this invention is to provide a latching mechanism including a plurality of latch bars and latch means or a rockable latch plate for simultaneously operating the latch bars.

Still another important object of this invention is to provide a new and improved lift type handle structure having a vertically moving latch plate actuator for operating a latching mechanism such as the disclosed type having a plurality of latch bars.

According to the general features of this invention there is provided a locker cabinet including a cabinet door having a movable handle mounted thereon, a latch plate fulcrumed on the door, superimposed latch bars mounted on the latch plate and having spaced diagonally offset pivots joining the latch bars with the latch plate generally on one side of the fulcrum, said latch bars being connected with latch and keeper mechanisms, and with said latch plate being connected to said handle on another side of the fulcrum, the handle being movable to rock said latch plate on its fulcrum and to cause said latch bars to operate said latch and keeper mechanisms.

According to still other features of this invention, a handle structure is provided which handle structure includes a pivotally mounted handle having a pin extending rearwardly of the handle and movable in an up and down direction with the pivoting of the handle, and a key operated lock including a pin latch which pin latch is swingable into and out of locking engagement with said pin upon operation of the key lock.

Other features of this invention relate to a latching mechanism including a handle housing, a lift type handle pivotally joined between its opposite ends at its sides with the housing, one handle end of the handle disposed within the confines of the housing and with an opposite handle end disposed outside of the housing for free pivoting movement with respect to the housing, the one handle end having a rearwardly projecting latch plate actuator movable in an up and down direction with respect to the handle for actuating a latch bar.

Other objects and features of this invention will more fully become apparent in view of the following detailed description taken in conjunction with the accompanying drawings illustrating a single embodiment and in which:

FIGURE 1 is a perspective view of a locker cabinet;

FIGURE 2 is a rear elevation of a locker cabinet door;

FIGURE 3 is an edge view of the locker cabinet door shown in FIGURE 2 only with parts broken away revealing details of a latching mechanism;

FIGURE 4 is an enlarged fragmentary rear elevation of the door and illustrating in full and dotted lines the operation of the latching mechanism;

FIGURE 5 is an enlarged fragmentary partially sectioned side elevation of a handle assembly including a lift type door handle, the section being taken substan-

2

tially on the line V—V looking in the direction indicated by the arrows, as shown in FIGURE 4;

FIGURE 6 is an enlarged fragmentary cross sectional view taken substantially on the line VI—VI looking in the direction indicated by the arrows, as shown in FIGURE 4;

FIGURE 7 is an enlarged fragmentary cross sectional view;

FIGURE 8 is an enlarged fragmentary rear elevation 10 of the door showing the latch bar and latch keeper in a closed position, similar to FIGURE 7; and

FIGURES 9, 10 and 11 are identical to FIGURES 4, 5 and 6 except that a modified type of latching mechanism is illustrated.

15 As shown on the drawings:

The reference numeral 10 indicates generally a locker cabinet having a locker door 11 mounted by means of hinges 12 thereon. The door 11 is illustrated as being comprised of sheet metal piece having rolled margins 13.

20 One of the rolled margins 13 is provided with a latching mechanism indicated generally at 14.

The latching mechanism 14 includes a handle assembly 15 as best seen in FIGURE 5. The handle assembly 15 includes a handle housing 16 and a lift type handle 17 is pivotally joined between its opposite ends at its sides with the housing 16 by means of the handle pivot pin 18. The housing 16 includes a housing recess 19 and a handle end 17a is disposed therein. An opposite handle end 17b lies outside of the confines of the housing recess for free 25 pivoting movement on pivot 18 for actuating a latch plate actuator or pin 20 secured to the upper handle end 17a. The pin 20 extends rearwardly in the housing recess 19 through door panel opening 11a on door panel 11b. The housing 16 is further provided with a handle rest or stop 21 and the handle has a shoulder 22 movable into and out of engagement with respect to the rest or housing stop 21.

30 The housing 16 has a key lock slot and a cylinder type key lock of any suitable type such as indicated at 23 is secured therein. The key lock includes a lock latch 24 which is swingable into and out of locking engagement with the pin or latch plate actuator 20 for controlling the operation of the handle. When the lock latch is secured with the pin, the handle may not be pivoted on its pivot 18 35 for it is locked in position in bottomed engagement against the housing stop 22.

35 The handle housing may be readily secured to the door panel 11b by means of metal screws 25 which are threaded through the door panel 11b into the housing 16 from the rear side of the door 11.

40 The latching mechanism 14 further includes a T-shaped latch plate or latch means 26 disposed at the rear side of the door panel 11b. The latch plate 26 is fulcrumed or pivoted on a fulcrum or pivot comprising a latch pivot pin 27 having a pivot pin plate 27a which is spot-welded or otherwise suitably secured to the door panel 11b, as indicated at 28" in FIGURE 4.

45 The T-shaped latch plate further includes stem and crosspiece portions 26a and 26b which are disposed generally at right angles with respect to one another. The stem portion 26a bears the latch plate pivot which pivot is disposed vertically of and disposed at one side of the latch plate actuator or pin 20. It will be noted that the latch plate and more particularly the stem portion 26a has a notch or recess 26c and that the pin 20 is secured therein. As the pin 20 is moved up and down by the operation of the handle 17, the latch plate 26 is caused to rock on its pivot 27.

50 An opposite end of the latch plate and more particularly the crosspiece portion 26b is secured with a pair of vertically disposed latch bars 28—28. To this end,

a pair of latch bar pins 29-29 are fastened to opposite ends of the crosspiece portion 26b and adjacent ends of the latch bars 28 are also secured with the latch pins 29.

A pair of latch bar guides or channels 30-30 are spot-welded at 31' (FIGURE 7) to the door panel 11b on vertically opposite sides of the handle 14. Each of the channels 30 has channel or guide legs 30a-30a provided with channel guide leg slots 30b-30b and each of the latch bars extends through the channel leg slots 30b-30b on one of the channels or guides 30.

It will be noted that each of the latch bars has a latch bar slot 28a located in the vicinity of an associated one of the channels 30 and that an upper edge 28b of the slot comprises a latch also indicated generally at 28b. Mounted on the cabinet at spaced intervals are keepers 31 which are shaped so as to be capable of being disposed in the channel defined by the guide channel 30 between its legs 30a-30a. As shown in FIGURES 7 and 8, it will be noted that when the door is in a closed position, that the keepers 31-31 are disposed within the channels 30 and that the latches 28b on the latch bars 28 are engaged with keeper slots 31a to lock the door against the cabinet body 10.

In the operation of the latching mechanism, it will be noted that when the latch bars are in a closed position, that the latch bars are offset with respect to one another and disposed generally in parallel relation. When the latches 28b are to be disengaged from the keepers 31, the latch plate 26 is caused to be rocked on its pivot by means of operating the handle and its latch plate actuator 20 whereby the latch bars 28 are disposed generally in vertical alignment with respect to one another as shown in FIGURE 2 whereby the latches 28b are disengaged from the keepers 31.

It will be further be noted from FIGURE 4, that when the latch bars 28 are disposed in a closed position that they are inclined slightly with respect to the door margin 13. When the pin 20 is moved downwardly through the elevation of the lower end 17b of the handle, the crosspiece portion 26b is caused to be elevated on fulcrum or pivot 27 as clearly shown by the full and dotted lines in FIGURE 4.

In FIGURES 9-11 is shown a modified type of latching mechanism indicated generally at 50. The latching mechanism 50 is identical to the latching mechanism 14 except that a modified type of latch plate 26' and a modified type of latch bar 28' are here employed. In the first form of my invention, a pair of latch bars 28 were employed whereas in this form the latch bar 28' comprises a continuous strip. The connection between the latch plate 26' and the latch bar 28' is further simplified since only a single connection is required instead of a dual connection as indicated at 29-29 in FIGURE 4.

The latch plate 26' is fulcrumed or pivoted on a fulcrum or pivot comprising a latch pivot pin 27' having a pivot pin plate 27a' which is spot-welded or otherwise suitably secured to the door panel 11b.

The latch plate 26' is angularly related with respect to the latch bar 28'.

The latch plate 26' has a "fork type" end 26a' which is secured to the latch bar 28' by means of a latch bar pin 29'. An opposite end of the latch plate 26' has a notch or recess 26c' and the handle pin 20 is secured in the recess in the same manner as previously described in connection with the first form of my invention.

The operation of the latching mechanism 50 is identical to the operation of the latching mechanism 14 except that the latch bar 28' moves vertically in generally a straight-line which is in direct contrast to the movement of the latch bars 28, as shown in FIGURE 4 of the first form of my invention. The latch bar 28' is provided with a latch bar slot 28a' including its upper edge 28b' for coaction with the keeper 31.

It will be understood that modifications and varia-

tions may be effected without departing from the scope of the novel concepts of the present invention.

I claim as my invention:

1. A latching mechanism for a locker cabinet comprising a handle assembly including a handle having a latch plate actuator extending rearwardly of the handle and movable with the handle, a T-shaped latch plate mounted on a latch plate pivot at the rear of the handle and spaced from said latch plate actuator with the latch plate actuator joined with the latch plate at one side of the latch plate pivot, said latch plate including stem and cross piece portions, vertically related latch bars having adjacent latch bar ends pivotally connected with opposite ends of said cross piece portion on an opposite side of said latch plate pivot, latch bar channels securable to a door panel and with each of said latch bars extending through vertically spaced channel legs, and keepers and latches associated with said latch bars, the latches being movable between said keepers and with said keepers each disposed between the legs of the channel and engaged by one of said latches, the handle being movable to cause the latch plate actuator to rock said latch plate on its pivot to move said latch bars and latches into and out of engagement with said keepers.

2. A locker cabinet including a door having a door panel and a latching mechanism mounted on said door panel, the latching mechanism including a handle assembly including a handle, latch means at the rear of the handle having a connection joining it with said handle, said latch means having a latch pivot mounted on the door panel spaced vertically of and disposed at one side of said connection on which said latch means is rocked upon actuation of said handle, a pair of latch bars having adjacent latch bar ends in pivotal assembly with said latch means on opposite sides of said latch pivot, latch bar guides secured to the door panel and with said latch bars extending through guide legs on said guides, said latch bars having latches movable with respect to said legs and keepers each disposed between guide legs on an associated one of said guides and engaged by one of said latches, said latch means upon being rocked on its pivot through actuation of said handle causing said latch bars to be moved for disengaging said latches from said keepers.

3. A locker cabinet including a door having a door panel and a latching mechanism mounted on said door panel, the latching mechanism including a handle assembly including a handle, latch means at the rear of the handle having a connection joining it with said handle, said latch means having a latch pivot mounted on the door panel spaced vertically of and disposed at one side of said connection, said connection on which said latch means is rocked upon actuation of said handle being disposed on one side of said latch pivot, latch bar means in pivotal assembly with said latch means on an opposite side of said latch pivot, latch bar guides secured to the door panel and with said latch bar means extending through guide legs on said guides, said latch bar means having latches movable with respect to said legs and keepers each disposed between guide legs on an associated one of said guides and engaged by one of said latches, said latch means upon being rocked on its pivot through actuation of said handle causing said latch bar means to be moved for disengaging said latches from said keepers.

4. A latching mechanism for a locker cabinet door comprising a handle assembly including a handle pivoted intermediate its ends, a pin disposed on one end of said handle, a latch plate pivoted on an axis extending in a direction at right angles to the direction in which the axis of the handle pivot extends, said pin interconnected with said latch plate on one side of the latch plate pivot, a latch bar means pivotally connected to said latch plate on the opposite side of said latch plate pivot, a keeper means with which said latch bar engages, said handle upon being rocked on its pivot operating to move

said pin and latch plate to disengage said latch bar from said keeper means, said latch bar means comprising a latch bar, said latch plate having a slotted end, a latch bar pivot pin secured to the latch bar between its ends and with said slotted end embracing said pivot pin, and a key operated lock having means for engaging said pin to prevent actuation of said handle.

5. A latching mechanism for a locker cabinet door comprising a handle assembly including a handle pivoted intermediate its ends, a pin disposed on one end of said handle, a latch plate pivoted on an axis extending in a direction at right angles to the direction in which the axis of the handle pivot extends, said pin interconnected with said latch plate on one side of the latch plate pivot, a latch bar means pivotally connected to said latch plate on the opposite side of said latch plate pivot, keepers with said latch bar engage, said handle upon being rocked on its pivot operating to move said pin and latch plate to disengage said latch bar from said keepers, latch bar guides secured to the door panel and with said latch bar

means extending through guide legs on said guides, said latch bar means having latches movable with respect to said legs and the keepers each disposable between said guide legs on an associated one of said guides and engaged by one of said latches upon latching, said latch plate upon being rocked on its pivot through actuation of said handle causing said latch bar means to be moved for disengaging said latches from said keepers.
